UNITED STATES PATENT OFFICE.

FREDERICK M. WHYTE, OF TARRYTOWN, NEW YORK.

CAR END CONSTRUCTION.

1,408,234.

Specification of Letters Patent. Patented Feb. 28, 1922.

Application filed December 4, 1920. Serial No. 428,183.

To all whom it may concern:

Be it known that I, FREDERICK M. WHYTE, a citizen of the United States, residing at Tarrytown, in the county of Westchester and State of New York, have invented a certain new and useful Improvement in Car End Constructions, of which improvement the following is a specification.

This invention relates to the formation of 10 a metal plate, such as pressed steel, for structural purposes, and particularly for use as the end of a railway freight car.

Various designs of pressed steel plates, having different arrangements of corrugations for stiffening, have heretofore been proposed and used for car ends, but my improvement relates more particularly to that type of plate provided with outwardly pressed panel portions having an outer surface parallel with the main sheet but spaced therefrom and integrally connected therewith by the side portions of the panels, the width of the panels being preferably about equal to the space between panels.

25 A structural metal plate of this type has been heretofore proposed in my prior application Serial No. 329,226, filed, October 8, 1919, and in which ribs are formed in the sheet at the ends of the panels for taking 30 up the excess metal at the corner. The object of my present invention is to provide an improved metal plate of this type, in which the panels may be more readily and easily formed by cold pressing or bending 35 of the plate without the necessity of heating the same, and without materially drawing or stretching the metal, and also wherein the side flanges may be flat and easily formed by bending the edges of the sheet at right

40 angles to the plane of the sheet and without the formation of ribs in the sheet. One of the features of my improvement comprises the tapering of the ends of the panels substantially to an apex at the sides or ends of 45 the plate for closing the ends of the panels. Another feature comprises the formation of cut-out portions or notches in the margins of the sheet opposite the ends of the panels for compensating for the metal taken up in the outward spacing or sides of the panels and also to facilitate the bending of the side flanges. Still another feature comprises

caps for covering the notches or slots in the margins of the sheet or flanges and at the ends of the panels for weather-proofing the 55 plate when desired.

In the accompanying drawings: Figure 1 is an end elevation of a box car showing my improvement applied thereto; Fig. 2, a side elevation of the end of the car showing 60 the flange of the plate; Fig. 3, a plan of a rectangular metal sheet or blank from which my improved plate is to be formed, said sheet having the notches cut in the side edges; Fig. 4, a plan, showing the sheet after the 65 panels have been formed but before bending the side flanges; Fig. 5, a transverse section taken on the line 5—5 of Fig. 4; Fig. 6, a side view of the sheet as shown in Fig. 4; Fig. 7, a corresponding side view after the 70 side flanges have been bent at right angles to the sheet; and Fig. 8, a corresponding side view with the caps applied at the ends of the panels.

According to my improvement, the plate 75 is designed to be formed from a plane rectangular metal sheet, 9, of the desired size and thickness, and the first operation consists in cutting notches, 10, in the side edges of the sheet, as shown in Fig. 3. The depth 80 of the notches is made equal to the width of the flange which is desired at the side edges of the plate, while the width of the notches will be determined by the depth of the panels, that is, by the amount of metal taken 85 up in forming the side edges of the panels and by which the outer face or parallel plane portion is spaced outwardly from the body portion of the sheet. The notches are formed in pairs at opposite ends of the sheet, 90 and in line with the proposed panels.

The panels, 11, are then formed by pressing or bending the metal sheet upon a suitable die or mandrel, the opposite ends of said panels being tapered at 12, to an apex at 95 the inner end of the notches, as indicated in Figs. 4, 5 and 6. In this operation, a certain amount of the metal is taken up in forming the side portions, 13, of the panels, and the side edges of the notches are brought very 100 nearly together, leaving only a narrow slot or opening from the apex of the tapered end of the panel to the margin of the sheet. This permits the operation to be easily per-

formed without material drawing or stretching of the metal, and without the necessity of forming ribs at the margin of the sheet.

The notched side edges of the sheet may then be readily bent down at right angles to the main body of the sheet to form the flanges, 14, as shown in Fig. 7, for securing the plate to the corner posts.

Where a weather-proof construction is desired, a cap, 15, is employed to cover the opening at the notch and the apex of the tapered end of the panel, as shown in Fig. 8, and these caps may be tightly secured to the face of the panel and to the flange by riveting, welding, or otherwise. The caps may also be so formed as to serve as stiffeners for reinforcing the flanges.

By means of this construction, the plate is so formed that the maximum portion of its area lies in two parallel planes at a maximum distance from the neutral axis, thereby producing a strong and rigid structure.

In the operation of forming the plate, the design is such that each panel may be formed independently of the others, by pressing or bending the sheet, whereby a minimum amount of force or power is required, particularly as the flanges at the side edges may be bent down after the panels are completed.

In order that there shall be sufficient clearance in the cut-out portions or notches to permit the formation of flat flanges at the side edges of the sheet, the width of the notches must be at least equal to the difference between the full width of the sheet, as indicated in Fig. 3, and the horizontal width after the panels have been formed, as indicated in Fig. 4, and this total difference must be divided equally among the notches at the ends of the panels. In practice, it may be desirable to make the notches of a slightly greater width than indicated by the above difference in theoretical measurements to provide for any inaccuracies that may occur in formation.

As shown in the drawings, each plate is formed with two panels, and the car end as shown in Figs. 1 and 2 is built up of two plates riveted together at their edges, the side flanges being suitably bolted to the corner posts of the box car. The top edge of the upper plate is, in this case, inclined at each side of the center to conform to the pitch of the car roof. In this construction, the caps, 15, are also employed for weather-proofing the plates at the notches at the ends of the panels and strengthening the side flanges. When used in the construction of open-top cars without roofs, such as gondola cars, a single plate may be employed, and the caps at the notches may be omitted as weather-proofing is not necessary, unless it be desired to retain them for strengthening purposes. Flanges may also be provided at the top and bottom of the plate, if desired.

Having now described my invention, what I claim as new and desire to secure by Letters Patent is:

1. A structural metal plate formed from a plane sheet and having panel portions spaced outward in a plane parallel with the main sheet and integrally connected thereto by the side portions of the panels, the ends of the panels being tapered in width, and of uniform depth. 70

2. A structural metal plate formed from a plane sheet and having panel portions spaced outward in a plane parallel with the main sheet and integrally connected thereto by the side portions of the panels, and notches or slots formed in the side edges of the sheet opposite the ends of said panels. 80

3. A structural metal plate formed from a plane sheet and having panel portions spaced outward in a plane parallel with the main sheet and integrally connected thereto by the side portions of the panels, said panels being tapered to an apex at their ends, and a cap for closing the opening at the apex of each panel. 85

4. A structural metal plate formed from a plane sheet and having panel portions spaced outward in a plane parallel with the main sheet and integrally connected thereto by the side portions of the panels, and notches formed in the side edges of the sheet opposite the ends of said panels, said side edges being bent at an angle to the main sheet to form flanges. 90

5. A structural metal plate formed from a plane sheet and having panel portions spaced outward in a plane parallel with the main sheet and integrally connected thereto by the side portions of the panels, the main sheet having notches or slots extending from the ends of the panels to the margin of the sheet, and caps for covering said slots. 100

6. A structural metal plate formed from a plane sheet and having panel portions spaced outward in a plane parallel with the main sheet and integrally connected thereto by the side portions of the panels, said panels being tapered to an apex at their ends, notches or slots extending from the apices of the panels to the margin of the main sheet, 115 and caps for covering said slots.

7. A structural metal plate formed from a plane sheet and having panel portions spaced outward in a plane parallel with the main sheet and integrally connected thereto by the side portions of the panels, said panels being tapered to an apex at their ends, notches or slots extending from the apices of the panels to the margin of the main sheet, 120 said notched side edges of the main sheet being bent at right angles to the main sheet to form flanges. 125

8. A structural metal plate formed from a plane sheet and having panel portions spaced outward in a plane parallel with the main sheet, 130

main sheet and integrally connected thereto by the side portions of the panels, said panels being tapered to an apex at their ends, notches or slots extending from the apices of the panels to the margin of the main sheet, said notched side edges of the main sheet being bent at right angles to the main sheet to form flanges, and caps for covering the apices of the panels and the slots in the flanges of the sheet. In testimony whereof I have hereunto set my hand.

FREDERICK M. WHYTE.
